5 Claims. (Cl. 5—81)

ABSTRACT OF THE DISCLOSURE

An elongated rescue carriage having a support thereon on which a prone injured person is adapted to be supported and secured, and which carriage includes ground-engaging wheels for movement over the ground or against a side of a cliff, in a direction longitudinally of the carriage. A rope connected at one end with power actuated means on the carriage is adapted to extend to a remote stationary point and power means on the carriage actuates said power actuated means for moving the carriage along the rope to said remote point.

This invention relates to a rescue carriage, and has for one of its objects the provision of a carriage including means for securing a disabled person thereto for transporting such person over the ground, and for elevating such person with safety, including the person making the rescue where the disabled person has fallen from a cliff or ledge or has fallen into a shaft or pit.

Where a person has been disabled by falling from a cliff or into a shaft, pit, or the like, and there is no ready access to such person except by means of a lowered rope, or stretcher, it has been customary to strap such person to a stretcher and to hoist the stretcher by means of a rope. However, the hoisting of such person and stretcher has either been by means of persons or by a mechanical hoist at the top of the cliff or pit. A helper may first be lowered by a rope to strap the disabled person to the stretcher that may be attached to the same rope, after which, the stretcher with the disabled person secured thereto may be elevated. The rope usually chafes against rocks or hard ground as it is drawn up with the stretcher attached thereto, and the stretcher may rotate when freely suspended, or may be dragged across the face of the cliff or side of a shaft, or may bang against such face or side if free to swing or rotate, to the further injury of the person strapped to the stretcher. Furthermore, usually a number of persons are required to effect the rescue.

One of the objects of the present invention is the provision of a rescue carriage and means associated therewith for overcoming the above-mentioned objections.

Other objects and advantages will appear in the description and drawings.

In the description, FIG. 1 is a top plan view of the rescue carriage.

FIG. 2 is a side elevational view of the carriage. FIG. 3 is an end elevational view of the carriage of FIGS. 1, 2 as seen from the right end of FIG. 2.

FIG. 4 is an enlarged, fragmentary cross-sectional view at line 4—4 of FIG. 1.

FIG. 5 is an enlarged, fragmentary cross-sectional view at line 5—5 of FIG. 1.

FIG. 6 is an enlarged, fragmentary cross-sectional view at line 6—6 of FIG. 1.

FIG. 7 is an enlarged, fragmentary view of a clutch mechanism for the winch.

In detail, the carriage of FIG. 1 comprises a pair of corresponding, horizontally spaced, opposed, horizontally elongated frames generally designated 1, each comprising parallel, vertically spaced, horizontally extending frame members 2, 3 (FIG. 2), the former being uppermost, and

2

U-bends 4 connect the corresponding ends of the members 2, 3 at each side of the carriage.

A row of ground wheels 5, along each of the members 3, support the carriage for movement over the ground when the carriage is generally horizontally disposed, and support the carriage against the side of a cliff, pit, or shaft when the carriage is generally vertical and is hoisted or lowered by a rope. These wheels are preferably rotatably supported on shafts disposed adjacent to the junctures between the lower ends of posts 7 that, in turn, extend between the upper and lower frame members 2, 3 along each side of the carriage, and which posts are rigid with said frame members at their ends. The posts 7 are in a row along each side of the carriage and the end posts of each row preferably are connected at their ends with members 2, 3 at approximately the junctures between the U-bends 4 and said members, hence the lower curved portions of the U-bends may engage any obstructions on the side of a cliff or shaft to slidably guide the leading end of the carriage onto the wheels when the carriage is either lowered or raised.

Horizontal cross frame members 8 (FIG. 1) extend between and are connected at their ends with the posts 7 of opposed pairs thereof. These cross frame members may also be in vertically spaced pairs extending between each pair of opposed posts, as indicated in FIG. 2. Additional conventional braces, trusses, gussets, etc. may be employed wherever necessary for rigidity and strength.

The area between the upper frame members and the end cross frame member 8 at the ends of the carriage is substantially oblong in outline and an oblong horizontally elongated stretcher generally designated 9, and having a frame 10 is adapted to be releasably held by straps 11 that connect the side pieces 13 of the stretcher frame to the upper side frame members 2 of the carriage frame for releasably suspending the stretcher from said side frame members and for also holding the stretcher in position relative to the carriage frame when the latter is in a vertically extending position with a disabled person secured on the stretcher.

Said stretcher frame 10 is covered with an oblong flexible support 14, that is secured along its margins to frame 10, such as of duck or canvas onto which support a person is adapted to be held by straps 15 of webbing or the like that are connected to the side frame members 2. These web-straps 15 are each in two sections, each of which is connected at one of its ends to a side frame member 2, and the other ends of the sections are adapted to be connected by a quick releasable clamp or buckle 16.

The canvas or duck cover 14 for the stretcher frame is cut away where the straps 11 connect with side pieces 13, and the stretcher frame 10 may have end pieces 17 connecting the ends of the side pieces. The canvas 14 along said end pieces may also be cut away at 12 to provide hand openings for hands to grip the end pieces for lifting the stretcher.

The head of the carriage is the left-hand end as viewed in FIGS. 1, 2, while the foot is the opposite end. A person lying on the stretcher would have his or her head adjacent to the head of the carriage, and on the stretcher at the head end, while the feet would be on the stretcher at the foot end. One of the web-straps 15 is positioned to extend across the chest and upper arms of a person while the other may extend across the body below the hips. The number of straps for so holding a person onto the stretcher and carriage may, of course, vary since there is no obstacle to providing more straps along the side frame members 2 if necessary or if desired. Each strap 15 is formed in two sections, each being secured at one end to one of the side frame members 2, and their opposite ends being

connectable by quick release buckles or clamps 16 similar to those used on seat belts.

A horizontal platform 18 is rigid with the carriage, being secured to and extending between a pair of cross frame members 8 in a position adjacent to the foot of the carriage and spaced below the stretcher. A small internal combustion engine 19 is secured on platform 18, which engine may include a conventional gear or sprocket and chain transmission 20 (FIG. 1) for driving a winch 23, that, in turn is mounted on platform 18, and conventional clutch means 24 (FIGS. 1, 7) may be provided for connecting the winch with the engine for driving the winch.

Any suitable manually actuatable control lever 26 (FIG. 2) preferably supported at one side of the head end of the carriage (FIG. 2) is connected by linkage 27 with a friction clutch 24 for connecting and disconnecting the winch with the power driven shaft 31 and a foot pedal 28 may be connected by linkage 29 with the winch for releasably holding the winch against unwinding when the clutch is disconnected and for controlling the descent of the carriage where it is being lowered from above and when the carriage is suspended from above, although such descent itself may be controlled by slipping the clutch 24. Such control means in themselves are not new. A pawl 21 (FIG. 7) secured on a rigid support on platform 18 also is adapted to releasably engage teeth on the clutch element secured to the winch as a safety measure for releasably locking the winch against unwinding when the engine is stopped or the clutch is disconnected.

The throttle on engine 19 is connected by any suitable linkage or connection 30 with a manually actuatable control lever 33 on control panel 34 that is adjacent to the head end of the carriage and on one side of the latter.

At the foot end of the carriage is a step 35 that projects laterally from frame 1 when the frame extends vertically with the head end uppermost, and this step is to provide a support for a person who is performing the rescue operation; hence the foot pedal 28 is readily accessible to a foot of such person, while the control levers 26, 33 are readily accessible to a hand of the operator. The side members 2 provide convenient means for either or both hands of an operator standing on step 35.

A rope 36 of wire, nylon, hemp, or any other suitable material, is connected with the winch drum 23 at one end and extends successively over grooved idler rollers 37, 38 that are respectively rotatably carried on shafts spaced below stretcher 9, and these shafts may provide two of the cross members 8. Roller 38 is closer to the winch drum than roller 37 and the rope is preferably reeved to extend over roller 37, then back to, and around roller 38, while any suitable yieldable levelling bar or guide 39 (FIG. 3) over winch drum 23 will automatically maintain the rope wound thereon in axially aligned adjacent coils. Roller 38 is positioned substantially on the longitudinal axis of the carriage and the rope 36 extends from said roller through a rope guide 40 (FIG. 2) positioned at the front end of the carriage midway between the ends of a cross member 43 (FIG. 1) that, in turn is secured at its ends to the U-bends 4 that are at the forward or head end of the carriage midway between the ends of said U-bends.

A hook 44, or any other suitable attaching means, is secured on the end of the rope 36 where it projects from the guide 40 outwardly of the carriage.

In operation, assuming a disabled person is at the bottom of a cliff or in a shaft or pit, one rescue operator, alone, having the rescue carriage at the top of the cliff may secure hook 44 to a truck, tree, post, or to any other stationary member, with the rope wound on the winch and the carriage brake set. The operator then may take his position on step 35 and release the brake and permit the carriage to descend to the disabled person. Whether or not the engine is started before the descent or afterward, is at the option of the operator, although if started

first, the clutch may be used to control the descent. In any event the locking pawl 21 must be released before the winch can be released for unwinding the rope 36.

At the bottom of the pit or cliff, or wherever the disabled person may be, the latter is lifted onto the stretcher and is strapped thereto by the web-belts 15. The operator may then start the engine and connect the clutch 24 for actuating the winch 23, and the carriage will be drawn to the base of the cliff with the person thereon, if the latter is some distance from the base. Then the carriage will be drawn up the side of the cliff or pit with wheels 5 against said side, as the rope is wound on the winch. The operator will be supported on the step 35 during the ascent with one hand in a position to control the speed of the ascent, or to stop the engine, if necessary, and if the latter occurs, the winch will, of course, be positively locked against unwinding.

At the top of the cliff or pit, the carriage will be drawn over the edge and the clutch may be disconnected or the engine stopped. The injured person may then be transported to a vehicle for transport to a hospital or may be treated.

It should be noted that the rope 36 is not chafed by this operation, and the illustration of a one-man operation is merely to emphasize that the invention provides means enabling such an operation. Obviously, several persons may use the device, and the provision of a detachable stretcher enables several persons to carry a patient to the carriage from a distance, or to carry the injured person a distance from the carriage to an ambulance or vehicle, should the circumstances require it, without removing the patient from the stretcher 9. Inwardly extending projections 42 (FIG. 4), rigid with the upper side frame members 2, enable the stretcher 9 to be supported by said frame members in a position for strapping the stretcher to the carriage.

The provision of engine 19 at the foot end of the carriage, and adjacent to the step 35 on which the operator is adapted to stand, provides a substantial weight at the lower end of the carriage when the latter is being hoisted, and the point of connection between rope 36 is adjacent to the engine, rather than at the head end of the stretcher. This arrangement, in combination with the position of the rope guide 40 materially stabilizes the carriage while it is suspended during an ascent or descent, since it is adapted to lower a disabled person from a height, as well as carry them upwardly.

The hook 44 may be similar to a grappling hook for automatically digging into the soil or ground, or for engaging rocks, a stump or other means may be available in an emergency.

It is obvious that the rescue device is equally applicable for drawing the carriage up gradual or up steep inclines, as well as for free suspension of the device by the rope from or past an overhang, and for lowering the carriage from a height.

Different conventional arrangements for the control of the engine and hoist may be used. This type illustrated is not to be considered restrictive.

While I have illustrated and described the invention in detail, I do not wish to limit myself to the precise details so shown and described, but desire to avail myself of such variations and modifications as may come within the scope of the appended claims.

65 I claim:

1. A rescue device comprising;

- (a) an elongated carriage having a head end and a foot end respectively at opposite ends thereof and an elongated support thereon adapted to support a disabled person prone thereon with the head of such person at said head end and with the feet at said foot end;
- (b) ground wheels rotatably supported on said carriage adapted to engage the ground below said support when said carriage and support are generally hori-

- zontal, or to engage the side of a cliff or pit at one side of said support when said frame is generally vertically extending or inclined relative to horizontal with said head end elevated, and means supporting said wheels on said carriage in positions spacing said support and said frame from said ground or side of a cliff or pit upon movement of said carriage longitudinally thereof, when said wheels are in rollable engagement with said ground or the side of a cliff,
- (c) a rope of sufficient length to extend from said carriage when the latter is at the base of a cliff or the like to the top of such cliff,
- (d) power actuated means on said carriage in a position spaced between said support and such cliff when said wheels space said support from the side of such cliff, and power means on said carriage connected with said power actuated means for actuating the latter to move said carriage along said rope, suspended from the latter, with said carriage in a generally vertically extending position and said head end leading,
- (e) manually actuatable control means on said carriage connected with said power actuated means for controlling actuation of the latter, said control means being in a position on said carriage for access to a hand of an operator in standing position on said carriage alongside the latter when the latter is in said generally vertically extending position,
- (f) means on said carriage for supporting an operator in said standing position alongside said support.
2. In a device as defined in claim 1;
- (g) means for supporting said power means adjacent to one end of said carriage,
- (h) guide means on said carriage at the head end thereof in a position substantially centrally between the opposite lateral sides of said carriage and in a plane spaced between said support and the side of a cliff against which wheels are adapted to engage when said carriage is suspended generally vertically for retaining said rope at said head end substantially centrally between the opposite lateral sides of said carriage for retaining said rope at said head end substantially centrally between said opposite lateral sides free from engagement with said support and a person on the latter during movement of said device along said rope,
- (i) rope attaching means outwardly of said carriage and guide means for releasably securing the end of said rope outwardly of said guide means and carriage to a stationary object resistant to movement under the tension of said rope as said carriage is moved along said rope by actuation of said power actuated means.
3. In a device as defined in claim 1;
- (g) said carriage including a spaced opposed pair of side frames extending from end to end of said carriage disposed in parallel planes each having an elongated upper frame member and an elongated lower frame member of substantially the same length extending longitudinally of said frames,
- (h) said support comprising an elongated stretcher separable from said carriage disposed between said upper frame members and including a stretcher frame,
- (i) means for releasably securing said stretcher frame to said side frame members,
- (j) means for releasably securing a disabled person prone on said elongated support in a position extending longitudinally of said carriage,
- (k) and in a position spaced from rope, power means and power actuated means.
4. In a device as defined in claim 1;
- (g) said carriage including a spaced, opposed pair of side frames extending from end to end of said car-

- riage disposed in parallel planes each having an elongated upper frame member and an elongated lower frame member of substantially the same length extending longitudinally of said frames, and U-bends in each of said frames connecting opposite corresponding ends of said frame members of each side frame with the convex sides of said U-bends facing oppositely outwardly,
- (h) said ground wheel being in rows respectively positioned along each of said lower side frame members,
- (i) the space between said lower side frame members being unobstructed and free from engagement with projections on the ground or side of a cliff upon movement of said carriage over the ground or up the side of such cliff when said wheels are in engagement with said ground and the side of such cliff.
5. A rescue device comprising;
- (a) an elongated frame having a flexible support of sheet material thereon extending longitudinally thereof for supporting a disabled person prone thereon,
- (b) means for releasably securing such person on said support,
- (c) a pair of parallel rows of wheels on said frame for supporting said frame for movement longitudinally thereof on the ground or against the side of a cliff and the space between said rows of wheels being free for unobstructed passage of projections on the ground or on the side of a cliff therepast upon side longitudinal movement of said frame,
- (d) said frame having a head end at one end thereof and a foot end at the opposite end,
- (e) power means carried on said frame at said foot end in a position spaced below said support and at a level above said wheels, and supporting means on said frame for supporting said power means in said position,
- (f) a winch on said supporting means connected with said power means for rotating said winch, and
- (g) a rope connected with said winch for winding thereon and for unwinding therefrom, said rope extending from said winch being spaced below said support and extending toward and past said head end for connection with a stationary support,
- (h) guide means on said frame at said head end for guiding said rope past said head end outwardly thereof in a direction longitudinally of said frame,
- (i) means on the said rope for connecting the end thereof that extends outwardly of said head end to a stationary support,
- (j) control means connected with said power means and supported on said frame actuatable for controlling said power means,
- (k) means on said foot end of said frame for supporting an operator thereon in standing position when said frame extends vertically with said foot end lowermost during movement of said frame upon actuation of said winch with the said rope extending past said guide means to an attachment above said frame,
- (l) means on said frame for manual grasping by an operator in said standing position, said means for supporting said operator being adapted to support said operator in a position facing said flexible support and facing a person secured on such support.
